TIMING MECHANISM

Foster E. Weld, Newton, Mass., assignor to The Gamewell Company, Newton Upper Falls, Mass., a corporation of Massachusetts

Application November 19, 1936, Serial No. 111,749

18 Claims. (Cl. 137—139)

The present invention relates to timing mechanisms and more particularly to apparatus of the general type disclosed in the patent to Smith No. 1,538,010 dated May 19, 1925. The apparatus therein described is a device for timing the operation of a valve and is especially useful as whistle-blowing device for fire alarm systems.

The object of the present invention is to improve the apparatus described in the Smith patent with a particular view towards simplifying the construction, insuring greater reliability and providing for greater precision and flexibility of the timing control. To this end the invention comprises the apparatus hereinafter described and particularly defined in the claims.

In the accompanying drawing, illustrating what is now considered the preferred form of the invention, Fig. 1 is a side elevation of the valve; Fig. 2 is a section on line 2—2 of Fig. 1; Fig. 3 is a horizontal sectional view on an enlarged scale; Fig. 4 is a sectional elevation; Fig. 5 is a detail sectional view as seen from the opposite direction of Fig. 4 and showing certain of the parts in operating position; and Fig. 6 is a detail to be referred to.

The illustrated embodiment of the invention comprises a whistle valve having a main casing 6 with an inlet chamber 8 connected to a source of pressure such as compressed air, and an outlet chamber 10 adapted to be connected to a whistle. Between the chambers 8 and 10 the casing is formed with an internal web 12 serving as a valve seat for the normally closed main valve 14. The main valve 14 is formed on the end of a sleeve 16 which is adapted to slide in the casing and which is connected at its outer end with a piston 18 in a cylinder 20. The cylinder 20 is closed by a plug 22. The arrangement is such that upon the application of pressure to the rear, that is, the right hand side of the piston 18 as viewed in Figs. 3 and 4, the main valve 14 is opened to connect the source of pressure with the whistle. The cylinder 20 is provided with a small exhaust port 24 at the rear of the piston so that atmospheric pressure is normally maintained thereon and is also provided with small vents 26 in front of the piston to prevent building up of pressure against movement thereof. The main valve is normally maintained closed, not only by the air pressure on its face, but also by a compression spring 28 which bears between the valve and a collar or bushing 30.

The operation of the main valve 14 is controlled by an intermediate valve which comprises a member 32 having a cone-shaped surface normally

seated in the opening at the center of the main valve. The valve member 32 is provided with a stem 34 received within the sleeve 16 and of somewhat smaller diameter to afford a passage for compressed air to the rear of the piston 18. Near 5 the left-hand end, as viewed in Figs. 3 and 4, the stem is provided with an enlarged portion 36 to engage the walls of the sleeve and serve as a guide for the intermediate valve. The portion 36 is provided with flattened surfaces to afford 10 passages for the air when the valve 32 is open. The stem 34 extends outwardly through an opening 37 in the closure plug 22 and near its end it has a portion 38 of reduced diameter. It will be seen in Figs. 3 and 4 that the space around 15 the relieved portion 38 of the stem normally communicates with the atmosphere. Upon a movement of the intermediate valve 32 to the left, as shown in Fig. 6, the outer end of the opening 37 is closed by the end of the stem 34 20 and the relieved portion of the stem then communicates at its inner end with the interior of the cylinder 20.

To effect an opening movement of the intermediate valve 32 the valve is provided with another stem 40 extending to the left and carrying at its outer end a piston 42. The piston 42 slides in a cylinder 44 which is formed in a casting 46 bolted to the main casing 6. The movement of the valve is limited by the collar 30 25 which acts as a stop to be engaged by the valve member 32. The collar is held against a suitably formed face of the casting 46. The casing 6 and the casting 46 are sealed by a lead gasket 48.

The cylinder 44 is normally supplied with the 30 same pressure as the inlet chamber 8 by a port 50 which, as shown in Fig. 3 extends from the chamber 8 through the casing 6, the gasket 48 and the casting 46. The port 50 communicates with a port 52 and a port 54 which lead into the 35 chamber 44 in back of the piston 42. The port 52 is in such position as to be covered by the piston 42 when the latter is moved to the left. The port 54 is adjustable by means of a needle valve 56 threaded into the casting and adapted 40 to be maintained in adjusted position by a suitable check nut. The port 52 is permanently closed by a taper plug 58. The chamber 44 communicates with a clean out passage 60 which is closed by a plug 62.

The parts as thus far described are maintained in the normal or inactive positions as shown in Figs. 3 and 4 by virtue of the air pressure in back of the piston 42 which maintains the intermediate valve 32 closed on its seat and thereby pre- 45

vents passage of compressed air into the cylinder 20 at the rear of the main valve control piston 18. To operate the main valve, it is necessary first to move the intermediate valve 32 to the left and this is accomplished by relieving the pressure in back of the piston 42.

The means for relieving the pressure in the rear of the piston 42 comprises a pilot valve in the form of a poppet valve 64 which is normally seated at the end of a passage 66 leading into the rear of the chamber 44. The poppet valve has a stem 68 on which is mounted a piston or sleeve valve 70, the front portion of which is received in a chamber 71 of slightly larger diameter than the chamber 66. The rear portion of the valve is of enlarged diameter, as shown at 72, to slide in a cylinder 74. An exhaust port 76 leads from both the front of the cylinder 74 and the chamber 71; the port is always in communication with the cylinder 74, but during certain phases of the operation of the apparatus its connection with the chamber 71 is cut off by the front end of the sleeve valve 70. A small vent 78 connects the rear of cylinder 74 to atmosphere.

It will be understood that the term "front", as applied to any element herein, means that portion thereof which is nearest to the inlet and outlet chambers of the main casing 6, and that 30 the term "rear" means that portion farther removed; thus, the front end of the cylinder 74 is the right end as viewed in Figs. 3 and 4.

The valve stem 68 is provided with a shoulder 80 in back of the poppet valve head 64. This shoulder is adapted to be engaged by the sleeve valve 70 to hold the poppet valve open when the sleeve valve is in its forward position.

The cylinder 74 is closed at the rear by a plug or cap 82 which is bolted to the casting 46. A 40 plunger 83 engaging the end of the valve stem 68 protrudes through the plug 82.

The poppet valve 64 is adapted to be opened by pressure applied to the protruding end of the plunger 83. This is preferably accomplished by 45 means similar to that fully described in the Smith patent above referred to, comprising an oscillating hammer 84 operated by toggle members 86 and 88, the latter of which is controlled by the armature 90 of an electromagnet. This 50 entire assembly is enclosed in a casing 92 attached to the casting 46. When the arm 89 is released the hammer 84 is rotated counter-clockwise to engage the end of the stem 68 and open the poppet valve 64. The lever 88 is thereafter 55 returned to its original position by a resetting or restoring rod 94 attached to a piston 96 which slides in a cylinder 98 formed in the casting 46. The cylinder is adapted to be connected under certain conditions to the air pressure supply, 60 as will be hereinafter described. The piston 96 is maintained in its normal position as shown in Fig. 4 by a spring 100.

The sleeve valve 70 and the restoring piston 96 are operated from the compressed air supply 65 when the intermediate valve 32 is opened. This is accomplished by a port 102 which is formed in the closure plug 22 and which communicates with the opening 37 in the plug. The port 102 connects with a port 104 formed in the main casing 6 and the latter communicates in turn with a port 106 in the casting 46, leading into the sleeve valve cylinder 74 in the rear of the enlarged portion 72 of the sleeve valve. Normally 70 the ports 102, 104 and 106 are inactive to transmit pressure to the rear of the valve 72, first

because the intermediate valve 32 is closed, and second because the valve stem 34 closes the inner end of the opening in the closure plug 22. Upon opening of the intermediate valve 32, however, the pressure is communicated from the chamber 5 8 to the rear of the sleeve valve 72.

A port 108 leads from the sleeve valve cylinder 74 into a port 110 which communicates with the restoring piston cylinder 98. This communication is established through a suitable opening 10 in the gasket 48. The port 108 communicates with either the front or rear of the cylinder 74, depending on the position of the sleeve valve member 72. When the valve is in its normal or rear position as shown in Figs. 3 and 4, the port 15 108 connects with the front of the cylinder and communication with the atmosphere is therefore established through the exhaust port 76. When the valve is in its front position, as shown in Fig. 5, the port 108 communicates with the rear 20 of cylinder 74.

The apparatus is provided with a timing chamber 112 which, as shown in Fig. 2, comprises a closed tube mounted on the casting 46. A port 114 leads from the poppet valve chamber 66 to 25 the timing chamber 112.

The operation of the valve is described as follows: Normally the parts are as shown in Figs. 3 and 4, the sleeve valve 70 being in its rearward or left-hand position, and the intermediate valve 32 being maintained closed by the application of full pressure in the cylinder 44 at the rear of the piston 42. When the operating lever 88 is released the hammer 84 strikes the plunger 83 and opens the poppet valve 64. A relief passage for the 35 cylinder 44 is thus established through the chamber 66 and the port 76. The pressure on the back of the piston 42 being relieved, the supply pressure on the front of the piston moves the entire intermediate valve assembly to the left until the 40 valve member 32 engages the collar 30, the intermediate valve is opened and pressure is communicated to the rear of the main valve piston 18. The main valve is then opened to blow the whistle. 45

The length of time the main valve remains open is determined by the time necessary for the restoration of balanced pressure on the intermediate valve piston 42. This timing action is effected in the following manner: When the intermediate valve opens, its stem 34 assumes the position of Fig. 6 to close the outer end of opening 37 in the closure plug and to permit communication between the cylinder 26 and the opening 37. Thus pressure is applied through the ports 102, 104 and 106 to the cylinder 74 in back of the enlarged portion 72 of the sleeve valve 70. The sleeve valve moves forwardly, so that it enters the chamber 71 as shown in Fig. 5, thereby closing off communication of that chamber with the 60 exhaust port 76. The engagement of the end of the sleeve valve with the shoulder 80 holds the poppet valve open. Compressed air flows through the ports 50 and 54 into the cylinder 44 and thence through the chamber 66 and the port 114 65 into the timing chamber 112. The port 52 is now covered by the piston 42, and the rate of flow is therefore governed by the adjustment of the needle valve 56. Ultimately, after a time determined by the rate of flow and also by the size of 70 the timing chamber, the pressure in the cylinder 44 rises to substantially the same value as that in the inlet chamber 8 and the piston 42 is moved forwardly to close the intermediate valve. The differential pressure necessary for closing the in- 75

termediate valve arises from the fact that full supply pressure is now applied to the whole rear surface of the piston 42, but to less than the whole front surface thereof, atmospheric pressure only being applied to the outer end of the stem 34. After closure of the intermediate valve in this manner, the supply pressure is cut off from the cylinder 20, which then exhausts through the vent 24, permitting the main valve to close. It will be understood that the vent 24 is only large enough to insure proper venting after the pressure is cut off through closure of the intermediate valve, and does not prevent the building up of pressure in the cylinder 20 during the time in which the main valve is to be held open. A feature of importance is the auxiliary port 52 which is uncovered by the piston 42 during the final portion of the movement of the intermediate and main valves, thus providing a rapid pressure equalization which reduces the tendency of the valves to chatter.

Concurrently with the building up of pressure in the timing chamber, as above described, pressure is also applied to the resetting cylinder 98. This follows the forward movement of the sleeve valve, the port 108 being then in communication with the cylinder 14 in back of the portion 72 of the valve. Since the cylinder in back of the valve is under pressure from the port 106, this pressure is communicated through the ports 108 and 110, to act on the resetting piston 96. The arm 88 is thus returned to its original position to be latched by the armature.

When the intermediate valve and the main valve close, the stem 34 is returned to its original position as shown in Figs. 3 and 4. The pressure is then cut off from the opening 37 of the closure plug 22, and the opening communicates with the atmosphere. The sleeve valve cylinder 14 then exhausts through ports 106, 104 and 102, as well as the vent 78. The relief of pressure from the back of the valve causes the valve to be moved rearwardly under the influence of the pressure in the timing chamber, and the poppet valve which is no longer held open by the shoulder 80 is closed by the pressure in cylinder 44. The vent 78 permits a quick return of the sleeve valve, but as explained in conjunction with the vent 24, it is sufficiently small so that the pressure can be properly maintained in the cylinder 14 when necessary. At the end of the rearward movement of the sleeve valve, the port 108 opens into the cylinder 14 in front of the valve portion 72. The restoring cylinder 98 and also the timing chamber 112 then exhaust to atmosphere through the cylinder 14 and the exhaust port 76. All of the parts are then restored to the normal positions of Figs. 3 and 4.

The duration of the blast may be varied either by changing the timing chamber to one of different size or by adjusting the needle valve 56. The needle valve adjustment alone affords a suitable range for most purposes. For example, in fire alarm systems the blast is usually of a duration of one-half to one and one-half seconds. With a timing chamber of suitable size this range may be readily accommodated by adjustment of the needle valve only. If a signal blast of longer duration is desired a timing chamber of larger volume may be substituted.

The whistle may be operated under manual control by means of a handle 116 pivoted on a bracket 118 which is mounted on the closure plug 22. The handle is provided with a foot 120 which is adapted to strike the end of the intermediate

valve stem 34. Upon depressing the handle the intermediate valve opens, followed by opening of the main valve in the manner above described. The timing control operates in a manner similar to that described for the automatic operation, except that the poppet valve is opened by the action of the sliding valve 70 and therefore the cylinder 44 is not relieved to atmosphere. The cylinder is, however, placed in communication with the timing chamber as before, and a timing cycle is established in accordance with the time necessary to building up the pressure in the timing chamber, but this pressure is thereafter ineffective to permit restoration of the intermediate valve until the handle is released. Thus the whistle may be operated manually for a blast of any length.

It will be seen that the mechanism in its general form and in the results attained is similar to that described in the Smith patent above referred to. There are, however, a number of important differences. In the first place, the sleeve valve 70 of the present invention is operated in both directions by air pressure as distinguished from the mechanical movement of the corresponding part of the Smith device in one direction. This makes for a simpler construction and more positive operation. Furthermore, the restoring piston 96 and the timing chamber 112 are connected at the proper times with the supply pressure as distinguished from the Smith construction in which both of these parts are supplied by leakage around the piston of the intermediate valve. These improvements permit greater precision of timing and less effect from the presence of moisture, frost or oil in the space between the intermediate valve piston and its cylinder. Furthermore, any leaks around the restoring piston 96 do not affect the timing and accordingly more clearance between the piston 96 and its cylinder may be provided to avoid trouble from sticking.

Although the apparatus has been described as used for blowing a whistle of predetermined length of blast, the invention may be equally well applied to a time-controlled valve for any purpose. In other respects also the invention is not to be considered as limited to the particular embodiment shown and described, but may be modified within the scope of the appended claims.

The invention having been thus described, what is claimed is:

1. A timing device comprising an inlet chamber, a piston, a cylinder in which the piston reciprocates, means for normally maintaining substantially balanced pressure on the piston, means for initially establishing a relief passage from the cylinder at one side of the piston, a second piston operable by pressure from said chamber for thereafter closing the relief passage, means for restoring the balanced pressure on the piston at a governable rate, said restoring means including a timing chamber in communication with the cylinder, and means operated by restoration of balanced pressure on the piston for cutting off pressure from said second piston to thereby cut off communication between the cylinder and timing chamber.

2. A timing device comprising a casing having an inlet chamber, a cylinder, a piston in the cylinder having a face acted upon by the pressure in the inlet chamber, the casing having a port leading to the cylinder at the opposite face of the piston, initiating means for establishing a relief passage from the cylinder, means for thereafter closing the relief passage, means for restoring

pressure in the cylinder through the port at a governed rate, a pressure actuated resetting device for the initiating means, and means forming a passage separate from said port for applying pressure to the resetting device.

3. A timing device comprising a casing having an inlet chamber, a cylinder, a piston in the cylinder having a face acted upon by the pressure in the inlet chamber, the casing having a port leading to the cylinder at the opposite face of the piston, initiating means for establishing a relief passage from the cylinder, means for thereafter closing the relief passage, means for restoring pressure in the cylinder through the port at a governed rate, a resetting piston for the initiating means, and a passage separate from said port for establishing communication between the inlet chamber and the resetting piston.

4. A timing device comprising a casing having an inlet chamber, a cylinder, a normally balanced valve operating piston, initiating means to establish a relief passage from one side of the valve operating piston, a resetting piston for the initiating means, the casing having a port between the inlet chamber and said one side of the valve operating piston and a port to establish communication between the inlet chamber and the resetting piston, means for closing said relief passage, and means for establishing pressure on the resetting piston through said second-named port.

5. A timing device comprising a casing having an inlet chamber, a normally balanced valve operating piston, means for initially establishing a passage for relief of pressure on one side of the piston, a sliding valve for controlling the relief passage, and means operated by movement of the piston to control communication between the inlet chamber and the sliding valve.

40 6. A timing device comprising a casing having an inlet chamber, a normally balanced valve operating piston, means for initially establishing a passage for relief of pressure on one side of the piston, a sliding valve for controlling the relief passage, and means operated by movement of the piston for applying pressure from the inlet chamber to the sliding valve to close the relief passage.

50 7. A timing device comprising a casing having an inlet chamber, a normally balanced valve operating piston, means for initially establishing a passage for relief of pressure on one side of the piston, a sliding valve for controlling the relief passage, means operated by the piston for controlling the application of pressure to the sliding valve whereby the relief passage is closed by the sliding valve after initial movement of the piston, and means for restoring pressure on the piston at a governable rate.

60 8. A timing device comprising a casing having an inlet chamber, a normally balanced valve operating piston, means for initially establishing a passage for relief of pressure on one side of the piston, a sliding valve for controlling the relief passage, means operated by the piston for controlling the application of pressure to the sliding valve whereby the relief passage is closed by the sliding valve after initial movement of the piston, and a timing chamber to govern the time of restoration of pressure on the piston.

70 9. A timing device comprising an inlet chamber, a normally balanced piston, means for initially establishing a relief passage on one side of the piston, a timing chamber, a pressure operated sliding valve to control the relief passage,

and means operated by the piston for controlling the application of pressure from the inlet chamber on the sliding valve.

10. A timing device comprising an inlet chamber, a normally balanced piston, means for initially establishing a relief passage on one side of the piston, a timing chamber, a pressure operated sliding valve to control the relief passage, means forming a passage leading from the inlet chamber to the sliding valve, and a valve operated by the piston and controlling said passage.

15 11. A timing device comprising an inlet chamber, a normally balanced piston, a valve at one side of the piston to be initially opened to establish a relief passage, a sliding member to control the relief passage, means forming a passage connecting the inlet chamber with the sliding member, a valve operated by the piston to control said passage, and means for re-establishing pressure on the piston at a governable rate.

20 12. A timing device comprising an inlet chamber, a normally balanced piston, a poppet valve to establish a relief passage from one side of the piston, a sliding valve to control the relief passage and having means to hold the poppet valve open, means forming a passage to apply pressure to the sliding valve from the inlet chamber, a valve operated by the piston to control said passage, and means for re-establishing pressure on the piston at a governable rate.

25 13. A timing device comprising an inlet chamber, a normally balanced piston, a poppet valve to establish a relief passage from one side of the piston, a sliding valve to control the relief passage and having means to hold the poppet valve open, means forming a passage to apply pressure to the sliding valve from the inlet chamber, a valve operated by the piston to control said passage, means forming a pressure restoring passage for the piston, and a timing chamber communicating with the pressure restoring passage.

30 14. A timing device comprising an inlet chamber, a normally balanced piston, means for initially establishing a relief passage at one side of the piston to unbalance the piston, means for restoring balanced pressure on the piston including a sliding valve, means forming a passage from the inlet chamber to the sliding valve, and valve means connected to the piston normally closing the passage and arranged to open the passage when the piston is unbalanced.

35 15. A timing device comprising an inlet chamber, a normally balanced piston, means for initially establishing a relief passage at one side of the piston to unbalance the piston, means for restoring balanced pressure on the piston including a sliding valve, means forming a passage from the inlet chamber to the sliding valve, and valve means connected to the piston normally closing the passage and arranged to open the passage when the piston is unbalanced, said valve means being arranged to relieve the passage to atmosphere upon re-establishment of balanced pressure on the piston.

40 16. A timing device comprising an inlet chamber, a normally balanced piston, means for initially establishing a relief passage at one side of the piston to unbalance the piston, means for restoring balanced pressure on the piston including a sliding valve, means forming a passage from the inlet chamber to the sliding valve, and a stem on the piston normally closing said passage and having a portion of reduced diameter to permit communication of the passage with the inlet chamber upon unbalance of the piston, the reduced por-

tion normally communicating with the atmosphere to relieve the pressure on the sliding valve when balanced pressure is re-established on the piston.

- 5 17. Valve mechanism comprising an inlet chamber, a main valve, a sleeve on which the main valve is mounted, an intermediate valve normally closing the sleeve, a main valve operating piston on the sleeve, a cylinder in which said piston reciprocates, a closure for the cylinder, a normally balanced piston for the intermediate valve, a stem connecting the normally balanced piston with the intermediate valve and extending through the sleeve and closure, the stem having a portion of reduced diameter normally communicating with the atmosphere but adapted to communicate with the cylinder when the intermediate valve is opened, and timing means controlled by the operation of said stem.
- 10 18. Valve mechanism comprising an inlet

chamber, a main valve, a sleeve on which the main valve is mounted, an intermediate valve normally closing the sleeve, a main valve operating piston on the sleeve, a cylinder in which said piston reciprocates, a closure for the cylinder, a normally balanced piston for the intermediate valve, a stem connecting the normally balanced piston with the intermediate valve and extending through the sleeve and closure, the stem having a portion of reduced diameter normally communicating with the atmosphere but adapted to communicate with the cylinder when the intermediate valve is opened, and timing means controlled by the operation of said stem. 5
